United States Patent Office.

ANDREW J. STOVER, OF SANDYVILLE, IOWA.

Letters Patent No. 74,444, dated February 11, 1868.

STOVE-FLUE SUPPORTER.

The Schedule referred to in these Letters Patent and making part of the same.

TO ALL WHOM IT MAY CONCERN:

Be it known that I, A. J. STOVER, of Sandyville, Iowa, have invented certain new and useful Improvements in Stove-Flue Supporters; and I hereby declare that the following is a true, full, and exact description of the same, reference being had to the accompanying drawings, and to the letters of reference marked thereon. In the annexed drawings, which make a part of this specification—

Figure 1 represents a side view of my flue-supporter.

Figure 2 is a plan view of the same.

Figure 3 is a plan view of the segments embracing the stove-pipe.

Figure 4 is a plan view of the washer-plate.

The letter A, fig. 1, represents a square plate of metal, with a hole in its centre to admit a stove-pipe; the edges of said pipe, around the hole, being serrated for the purpose of diminishing the degree of heat communicated from the plate A to the pipe. b b designate two semicircular pieces of metal, with flanges on their inner edge, which flanges will be inserted in the hole made for the pipe, and made to embrace said pipe. In order to admit the air to circulate between the plate A and the flanges on b b, a series of openings will be made in A, where it comes in contact with said flanges. By this arrangement the plate A will be less affected by the radiation of heat from the stove-pipe. The plate A is perforated near each of its angles in order to receive the four iron bolts d, which said bolts are designed to pass through proximate joints and through the washer-plates e, and secured in their position by nuts g. The plate being now in condition to bear any superincumbent weight, the flue may be built upon it without any danger of its communicating fire.

Having thus described my invention, what I claim, and desire to secure by Letters Patent, is—

The plate A, the segments b b, the bolts d, and washer-plates g, the whole combined and operating as and for the purpose herein described.

In testimony whereof, I set my hand in presence of two witnesses.

ANDREW J. STOVER.
